UNITED STATES PATENT OFFICE.

CHARLES C. HARTUNG, OF ST. LOUIS, MISSOURI, ASSIGNOR TO EDWARD WALSH, JR., OF SAME PLACE.

DESIGN FOR SHEET-GLASS.

SPECIFICATION forming part of Design No. 31,700, dated October 17, 1899.

Application filed September 25, 1899. Serial No. 731,681. Term of patent 14 years.

To all whom it may concern:

Be it known that I, CHARLES C. HARTUNG, a citizen of the United States, residing at the city of St. Louis, State of Missouri, have invented a certain new and original Design for Sheet-Glass, of which the following is a full, clear, and exact description, such as will enable others skilled in the art to which it appertains to make and use the same, reference being had to the accompanying drawings, forming part of this specification, in which—

Figure 1 is a plan view of a piece of glass ornamented and configured according to my new and original design. Fig. 2 is a sectional view on line 2 2, Fig. 1; and Fig. 3 is an edge view.

This invention relates to a new and original design for sheet-glass, the essential characteristics of which are raised ribs arranged

on the face thereof, said ribs being approximately parallel in serpentine lines.

In the drawings, A indicates the body of the sheet of glass, and B the ribs on one face thereof, said ribs being arranged in serpentine lines and approximately parallel with each other. These ribs, as shown, are provided with inclined faces.

What I claim is—

The design for sheet-glass substantially as herein shown and described. 30

In testimony whereof I hereunto affix my signature, in the presence of two witnesses, this 13th day of September, 1899.

CHARLES C. HARTUNG.

Witnesses:

Wm. H. SCOTT,
F. R. CORNWALL.
